VACUUM CLEANER

James N. Baker, Baltimore County, Md., assignor
to The Black and Decker Manufacturing Com-
pany, a corporation of Maryland

Application November 29, 1941, Serial No. 421,013

9 Claims. (Cl. 183—37)

The invention relates to a vacuum cleaner which is adapted to meet the difficult conditions encountered in industrial plants, warehouses, and the like, a field for which it has been developed and to which it is particularly well adapted being cleaning work on automobiles and around garages and automobile wash stands, filling stations, and the like, including both wet and dry work. The various novel features are used in the combinations shown, but are also capable of more general application.

Important advantages of the improved apparatus include the provision of a construction and arrangement which is satisfactory for use in handling liquids as well as in the separation of other foreign particles from the cleaning air draft. For this purpose the motor is fully protected being entirely out of contact with the incoming draft and the material separated therefrom, cooling of the motor being accomplished by an air draft which reaches the motor by a path separated from the cleaning elements of the apparatus.

It is also of advantage that the clean air be caused to swirl as it enters giving a vortex action which tends to drop the heavier particles. The incoming dirt laden air, in accordance with the preferred arrangement, then passes in an upward direction through a baffling or straining device to remove medium weight particles before encountering the bag or filter fabric. The term, particles, is applied both to solids and liquids but the baffles are of particular advantage in separating liquids.

A further important contribution to the improved result attained is due to the arrangement of the bag or similar filter in the form of a series of convolutions by means of inner and outer bag stretchers whereby a relatively large area of the bag or similar filter material is exposed in filtering relation to the air draft without increase of tank volume so that the maximum amount of dust is taken from the air with a minimum of restriction to air flow thus giving a high degree of vacuum and maximum air flow in proportion to the power consumed.

It is also of advantage that the bag support and the inner and outer opposed bag stretchers are so arranged that the bag is placed automatically under tension as the apparatus is assembled being preferably in the form of a plurality of approximately concentric filtering partitions or walls separating and defining alternately arranged filter chambers, which may be divided into two sets of inner and outer chambers, one set be-

ing open to the intake and the other set to the vacuum.

It is also of importance that the apparatus not only provides efficient separation in a small space but that it has a large space for accumulation of debris. It is also notable that the tank is economically constructed of sheet metal of different thickness in the different areas according to conditions presented and the preferred construction includes a skirt to protect the castors on which the machine stands and to prevent capsizing.

Another feature of interest is that the motor and fan and discharge pipe are in a single unit which is first removed in disassembling and that this unit is adapted to stand on the floor and to supply, when thus removed, an air draft adapted to cleaning the bag and to other purposes. The unit referred to may be combined with the tank cover, the tank and cover being for convenience included under the term container. These and other features will be more fully brought out in the description and defined in the claims.

In the accompanying drawings, I have illustrated examples of the machine to which the invention may be applied, including a preferred and a modified form.

In the drawings:

Fig. 1 is an elevation of the machine, the internal construction being indicated in broken lines, the drawing being on a reduced scale,

Fig. 2 is a fragmentary view in the nature of a section on a radial plane of the apparatus, the scale being relatively enlarged,

Fig. 3 is a top plan view of the apparatus as shown in Fig. 1,

Fig. 4 is a fragmentary top plan of a baffle plate removed,

Fig. 5 is a fragmentary section on the line 5—5 in Fig. 4, drawn to an enlarged scale,

Fig. 6 is a horizontal section looking downwardly from the line 6—6 in Fig. 2, and showing the cleaning draft fan arrangement,

Fig. 7 is an elevation of the filter plate assembly and intermediate bag stretcher,

Fig. 8 is an elevation of the bag support removed,

Fig. 9 is an elevation of a modified form of bag stretcher and support removed, and

Fig. 10 is a section corresponding to Fig. 2 showing the machine with the bag stretcher Fig. 9, included.

Referring to the drawings by numerals, each of which is used to indicate the same or similar parts in the different figures, the construction shown, considered in a general way, comprises a

tank 1, a cover assembly 2, which assembly includes the motor 3, motor housing 4, motor cooling fan 5, cleaning fan assembly 6, and inner bag stretcher 7. The construction further includes baffle plate assembly 8 seated in the tank and having intermediate bag stretcher 9 mounted thereon and outer bag stretcher and support 10 on which the filter 11 is mounted, being placed under tension between the stretchers as the apparatus is assembled in a manner to be described.

It being understood that the elements of the machine as above catalogued and its details and arrangement are subject to variation, these elements and these details and arrangements will now be more specifically described.

The tank 1, in the preferred form shown, consists of a downwardly tapering or inverted frustoconical bottom section 12 which may be of relatively heavy sheet material as steel, and a top cylindrical body portion 14 of lighter gage steel.

The construction shown also includes a skirt 15 flaring outwardly and downwardly from the bottom section or member 12 and preferably of the heavier sheet material. The top, bottom and skirt members are secured together along a horizontally extending zone 16 in any suitable manner as by welding or the like.

Between the skirt 15 which extends down to or slightly below the bottom of the tank at 12" and the inclined wall 12' of said section is an annular chamber 19 which conveniently encloses castors 17 on which the apparatus is supported and rolled about. The castors 17 are mounted in brackets 17' secured to and extending downwardly from horizontal struts 18 extending radially across the annular space 19 and welded or otherwise suitably secured at their ends. The flaring skirt 15 by contact of its bottom edge 15' with the floor or other supporting surface serves to prevent capsizing of the apparatus, and also to shield the castors and to protect the lower end or bottom section of the tank from damage.

As a convenient means of covering, the top edges of the joint at 16, the tank is shown as provided with a circumferential externally convex bead at 20 and at a somewhat higher elevation there is an externally concave circumferential bead or indentation 21 which supports the baffle plate assembly 8 as hereinafter further described.

The tank 1, in the form shown, is provided with a tangentially arranged inlet at 40, Figs. 1 and 3, provided, as shown, with a fitting or nipple 41 for convenient attachment of the hose in a manner permitting it to be quickly detached and applied to the discharge fitting when it is desired to operate by blowing instead of by suction as in cleaning the bags and for other purposes.

The tangential arrangement of the inlet 40 which is preferably located well above the bottom of the tank, in operation sets up a circular current or vortex in the tank 1 which tends to separate the larger particles and drop them to the bottom of the tank where the air is but slightly disturbed if not absolutely still. The bottom taper at 12' contributes to the result, and the vortex may be otherwise attained.

The cover assembly 2 includes a cover casting 22, which, in the form shown, has a depending peripheral flange 24. This is circular in outline, the entire apparatus being preferably circular in cross section or in plan, as shown. This depending flange 24 takes over and encloses an approximately horizontal outwardly disposed top

flange 25 formed on the top edge of the tank 1. The cover casting 22 is also provided, in the form shown, with a downwardly disposed shoulder 26 which is spaced upwardly above the bottom edge of the depending flange 24 providing an annular chamber or groove 27, said shoulder 26, flange 24 and chamber 27 extending entirely around the cover.

In the assembled relation, the top edge of the bag support 10 indicated at 28 is flanged outwardly in a horizontal plane and enclosed in a rubber bead 29 which rests on the top horizontal flange 25 of the tank and supports the cover 2, the shoulder 26 bearing downwardly on the bead 29 oppositely to the tank flange 25.

In this way the bag and support 10 and 11 are held in the tank secured between the top edge of the tank and the shoulder or seat 26 on the cover and thus capable of instantaneous removal when the cover is removed.

In the form shown, the cover also includes a centrally located cleaning draft fan housing or chamber 30 which is open at the top into an annular discharge chamber 31 which surrounds the fan housing and has an upwardly disposed or other suitable discharge opening 32 for the cleaning draft. This opening is shown as provided with a fitting 33 in the form of a nipple to which the hose is detachably secured, as when and if, it is desired to use the apparatus as a blower instead of the regular suction cleaning operation more generally performed with such apparatus.

This fan chamber or housing 30 is extended downwardly and closed at the bottom by a bottom cover member 34 secured by bolts 35 or in any suitable manner, this cover is open at the center at 36 to admit the cleaning air draft which is drawn upwardly from the tank, passing from the vortex zone at the level of the inlet 40 upwardly through the baffle plates comprising the assembly 8 and through bag 11, to be further described, to this passage 36.

The bottom cover member 34, in the form shown, supports the inner stretching ring 7 spaced downwardly therefrom in any convenient manner as by means of legs 38 as clearly shown in Figs. 1 and 2. This stretcher ring or top stretcher enters the bag 11 and engages the bottom of the bag performing the final bag stretching operation as the assembling of the apparatus is completed, the cover being finally locked in position in any suitable manner as by means of latches shown in Fig. 1 at 44 distributed around the cover; such latches being a commercial product do not require specific description. It may be noted at this time that the cover is shown as provided at diametrically opposite points with projecting ears 45 which serve as handles and the apparatus is provided with brackets 46 and 47 for supporting the cable and hose when it is desired to coil them about the apparatus.

The motor 3 is enclosed in a housing 4. This housing 4, in the form illustrated, is supported on the cover casting 22 at the top center on a suitable seat 48, the motor housing 4 being correspondingly flanged at 49 and secured by bolts 50.

The seat 48 at the top center of the cover casting 22 is shown as grooved or channeled radially at 51, Fig. 2, to provide for the discharge of the motor cooling draft which enters the motor housing by way of slots 52 at the top, being drawn downwardly by fan 5. The motor 3 is supported in the housing 4 in a suitable manner as by means

of vertical screws 54 threaded upwardly into bosses 54' near the top of the housing, and the axis of the motor is upright and preferably aligned with the axis of the tank and cover, dislocation and rearrangement in the nature of changes of design being immaterial.

The motor shaft is connected in any suitable manner to a drive shaft 55 on which, in the preferred form, the motor cooling fan 5 is mounted, being located in a suitable fan aperture 56 in the bottom wall 57 of the motor housing 4. The object being, as already pointed out, to cool the motor by an air draft which is entirely separate and independent of the cleaning air draft so that the motor is fully protected at all times from grit, dust or liquids which may be handled by the cleaner. The cooling air is, in the form shown, discharged through openings 51.

In accordance with the preferred construction, the top wall 58 of the cover casting 22 is closed so that there is no exchange of air between the cleaning area of the apparatus, particularly the discharge chamber 31, and the motor housing 4. This construction may be said to contribute to the improved result attained by the down draft arrangement described whereby the motor is cooled and protected from the foreign substances which are separated from the air draft in the cleaning process. It will be understood, however, that the direction and source of the motor cooling draft would tend to protect the motor but it is of advantage to have wall 58 imperforate.

As shown, the shaft 55 extends downwardly through bearing 60 in the top wall 58 of the cover casting 22 which is also the top wall of the discharge chamber 31 and this shaft has mounted thereon, in the form shown, a plurality of spacing sleeves 61 and 62 and collars 63 and 64, forced upwardly against a shoulder 63' and clamped, as hereinafter described, by means of a nut 65 threaded on the lower end of shaft 55.

The cleaning draft fan assembly or fan is of the centrifugal type with a central intake at the bottom at 36, see Fig. 2, and a peripheral discharge at the top into discharge chamber 31, which has a discharge opening 32 and discharge fitting 33.

The fan, as shown, certain details being matters of design and subject to variation, has three rotary blade members 66, each comprising a supporting disc or plate 67 shown as at the top of each said blade member and secured to the shaft 55 in any suitable manner as by spacing sleeves 61, 62, and collars 63, 64 between the adjacent axial ends of which the inner central edges of said discs 67 are inserted and clamped by the pressure nut 65. Each rotary blade member also includes a set of fan blades 68 extending outwardly from and having their inner ends 68' spaced outwardly from the axis and inclined backwardly, i. e., oppositely to the direction of revolution and each set of blades 68 is shown as of considerable extent in the direction of the fan axis which in this instance is upright and the blades are connected and reinforced by a ring plate 69, the central opening of which at 69' surrounds the corresponding sleeve 61, 62. The outer ends of rotary fan members are of less radius than chamber 30 leaving a peripheral edge space 75, see Fig. 6. Between each pair of adjacent rotary blade members 66, the construction shows a stationary blade member 70 of which there are two in the construction shown. Each stationary blade member has a supporting ring plate or disc 71, 71' of the full diameter of the fan cham-

ber 30, shown as at the top of the blade member. These are clamped in the fan chamber by the spacing cylinder 72 which bears at its opposite ends against the outer peripheral edge portions 5 of both said plates 71, 71' whereby the upper stationary fan supporting plate or disc 71 is forced upwardly against a peripheral shoulder 73 in chamber 30, the disc 71' of the lower stationary fan member, being forced upwardly against the bottom edge of spacing cylinder 72 by the bottom cover 34 of the fan chamber which, as shown, may have an upwardly projecting rim 74 for this purpose, this rim is forced upwardly by tightening bolts 35.

10 15 Each stationary fan blade member 70 includes a set of fan blades 76, see Fig. 6, which may be of a contour and radius similar to that of the rotary blades 68 and of similar extent in the direction of the fan axis. As shown, each set of stationary blades 76 is connected and reinforced by plate or disc 77 of an outside radius similar to that of the two sets of fan blades 68 and 76 which is also the outside radius of the top and bottom discs or plates 67 and 69 of the rotary 20 25 fan blade members 66. These discs or plates 77 are centrally apertured at 77' to clear slightly the spacing sleeves 61, 62 of the rotary blades, but the supporting or top discs or plates 71, 71' of the stationary blade members 70 and the bottom discs 30 35 39 40 45 50 55 60 65 70 75 77 78 79 80 81 82 83 84 85 86 87 88 89 90 91 92 93 94 95 96 97 98 99 100 101 102 103 104 105 106 107 108 109 110 111 112 113 114 115 shown and stretches or spreads the bag downwardly and outwardly.

The intermediate stretcher 9 is shown as in the form of a cup open at the top at 85 and having as to its top edge an upward and outward curvature at 86 similar to the formation of the bag support at its bottom edge 84'. The intermediate bag stretcher or spreader is shown as perforated substantially throughout its area, the purpose of the perforations as in member 10 being to pass the air, said perforations being indicated by reference character 87. For convenience of construction and particularly to provide a support, the intermediate bag stretcher 9 has a bottom wall 88, as best shown in Figs. 2 and 7. Other supporting means may be provided. In the form shown bolts 89 are passed through this bottom wall and downwardly through spacing sleeves 90, 91, 92, 93, which serve to space the baffle plates 95, 96, 97, 98 respectively in the manner shown, the set of plates being held in assembled relation by said bolts and by nuts 99 threaded on the bottom ends of the bolts 89. The bolts 89 are passed through plates 95, 96, 97, 98 which are between the adjacent ends of said sleeves. Top sleeves 90 serve to space the stretcher 9 upwardly from top plate 95.

The baffle plates 95, 96, 97, 98 forming the assembly 8 are of a form and area to close the cross section of tank 1, which, in the form disclosed, is circular, and they are supported in the tank in the form shown by contact of the bottom baffle plate 98 at its outer peripheral edge with the peripheral concavity or inside bead 21, see Fig. 1, already described. Any suitable support may be provided.

In this way the entire baffle plate assembly and the intermediate or bottom bag stretcher may be supported in the apparatus, in the manner suggested in Fig. 1, the preferred details being more fully illustrated in Figs. 2 and 7. These terms top and bottom are used on account of contact with the top or bottom surfaces of the bag, i. e., inner and outer surfaces.

The inner or top stretcher ring 7 has already been described. This ring is supported on legs 38 extending downwardly from the bottom cover 34 of the fan housing and it may be noted in this connection that the lower outer contour of this ring is preferably curved as indicated at 100 in Fig. 2 to give satisfactory contact with the bag. The bottom edge of the ring 7, as previously described, is adapted to engage the floor or other support and to hold the cover assembly including the motor 3 and cleaning fan assembly 6, discharge chamber 31 and discharge fitting 33 in a fixed and operative position relatively to the floor, facilitating the use of the discharge 33 with or without the hose or nozzle for cleaning the filter bag and for other blowing operations without the tank and filter and baffles, etc., and hence without the resistance or restriction resulting therefrom.

As illustrated, the dust bag or filter 11 is preferably frustoconical though its shape would be determined by the shape of the bag stretchers, shown as the outer stretcher and support 10, the intermediate stretcher or bottom support 9 and the upper or inner stretcher 7. The alternate stretchers are oppositely disposed, that is, the outer stretcher 10 or bag support engages the inside of the bag with a downward thrust. The intermediate stretcher or support 9 engages the outside of the bag with an upward thrust and the inner stretcher engages the inside of the bag

with a downward thrust. These respective thrusts are applied or reach their maximum when the apparatus is brought to assembled relation and clamped. As thus spread or stretched, tension being desirable, the bag is arranged in approximately concentric chambers C, C¹, C², C³, which may be referred to as sets of alternate air supply and discharge chambers separated by the bag walls. The chambers of one set, C and C² being outside the bag and the chambers of the other set, C¹ and C³, being inside the bag. This arrangement gives the maximum area of efficiently presented filter fabric in the minimum space.

By reference to Fig. 4 it will be noted that baffle plate 95 is similar to the other plates 96, 97, 98 and it will be noted that these plates are provided with small trap holes or openings 102, each of which is formed by cutting a tongue of metal 103 on three sides and bending it downwardly. In the preferred form, Figs. 4 and 5, these lips are inclined downwardly and in the direction of the air draft which enters at 40, see Figs. 1 and 3. These trap openings 102 in the form shown are arranged in a series of concentric circles 105. The arrows in Fig. 5 show the relative direction of the vortex or circular air current due to the vacuum created by a fan assembly 6 and tangential direction of inlet 40, 41. The lips 103 also cause eddy currents adjacent openings 102 through which the vacuum draws the air, cleaned of practically all but the fine particles of foreign matter. The baffle plates need not be of identical construction or of any fixed number.

In operation, it being assumed that the apparatus has been entirely disassembled, the tank being empty, the baffle plate assembly 8 and the intermediate bag stretcher 9 are first inserted, the bottom baffle 98 resting on the inner bead or peripheral concavity 21. The outer bag stretcher or support 10 with the bag 11 mounted thereon and secured as described but extending beyond its bottom edge 84', the excess material being loosely arranged, is next inserted. The loose or free end of the bag is thus turned upwardly from said bottom edge 84' over the top edge 86 of the bottom or intermediate bag stretcher 9 extending the bag over the outer surface of stretcher 10 and providing a free unbacked and unobstructed zone 11' between circular curved edge 84' and similar edge 86. While the term concentric has been applied to the bag stretcher and chambers C, the meaning intended is not that the stretchers are necessarily coaxial or circular but ring-like or hollow and adapted to be brought to assembled relation by passing one through the other to arrange the bag in a series of similarly shaped convolutions. The ring like form is preferred, though other convolutions are contemplated. The term ring or ring-like, or hollow, is intended to include various closed bands or dished members which may be square, oval, polygamal, irregular or circular.

The cover assembly having been combined in the manner described, the top or inner bag stretcher ring 7 carried thereby in the manner shown and described is pressed downwardly with said cover assembly, the ring 7 entering into the portion of the bag 11 at the center bottom which will have subsided into the upper area of cup shaped bag stretcher 9. The cover assembly is then lowered until its downwardly disposed peripheral shoulder 26 rests on the bead 29 or otherwise on the top edge of the bag support 10,

which, in the position described, rests on the top horizontal flange 25 of the tank, being clamped when the cover is latched in closed position.

The cover assembly 2 being brought down into position is clamped by operation of the latches 44, which are distributed around the periphery of the cover and tank, whereby the assembly is completed.

The electric cord or cable 104 is shown as wrapped around the hooks 46 at the top of the tank in Fig. 3. The hose which may be attached for suction cleaning to the fitting 41 or for blower cleaning to the fitting 33 and provided with the usual set of suction and blower nozzles is not shown. It may be coiled and supported by hook 47.

It is also notable that the vortex action of the air in the zone of the tank in which the inlet 40 is located, tends to separate the larger particles in the initial operation, the lower portion of the tank in the zone around 12' containing air which is practically quiescent so that the particles which are thrown out or dropped by the vortex action are deposited in the bottom area and remain until removed.

It is also notable that the cleaning draft is upwardly disposed and that the force of gravity tends to separate the solids as the air is advanced upwardly having a similar and even more important effect in the separation of liquids, which are most desirably retained in the bottom of the apparatus.

Above the vortex area around the nozzle, the air draft encounters the baffle plates 95, 96, 97, 98 with their trap openings 102 through which the air escapes, the depending lips 103 tending to contact the particles more particularly the medium sized particles and deflect them downwardly whereby they are dropped or retained between the baffles depending on the location of the point of separation.

When the air reaches the filtering chambers C and C², which are on the intake side of the bag, the bulk of the foreign matter, except the very fine particles, will have been separated.

It will also be apparent that by this construction and arrangement, a larger area of the bag is operatively arranged in smaller area giving a filter of high capacity in a relatively small space, at the same time the tank provides a relatively large space for debris in which the air is caused to swirl giving a vortex action to separate the heavier particles.

It is also notable that while the baffles are particularly effective in removing moisture, they also serve to remove the medium sized particles of dirt.

In Figs. 9 and 10, I have shown a bag support and/or outer bag stretcher 110 which is similar to the bag support or stretcher 10 previously described, except that it is provided with outwardly projecting ribs or bag distenders 106 distributed over its surface so that the bag 11 is spaced outwardly from the wall at 107 of the support making the area of the bag outside of the support one hundred percent effective as a filter by avoiding any tendency to limit the effective area of the bag on the outside of the support, to the perforations, i. e., to the area comprised by the perforations themselves. In other words, the outer surface of the support does not block the pores of the fabric as it may be said to do where the fabric is in close contact with said surface.

The two forms of apparatus shown are dis-

closed as examples only of the application of the invention, the description being so worded as to enable those skilled in the art to construct this and other apparatus for the practice of the invention.

I have thus described a preferred and modified apparatus embodying the invention, the description being specific and in detail in order that the manner of constructing, applying, operating and using the invention may be fully understood; however, the specific terms herein are used descriptively rather than in a limiting sense, the scope of the invention being defined in the claims.

What I claim as new and desire to secure by Letters Patent is:

1. A vacuum cleaning apparatus comprising a tank and a cover therefor, a filtering bag extending into the tank, a plurality of bag stretchers of different diameters supporting said bag in approximately concentric convolutions in said tank, one of said stretchers being a separate removable frame extending within the inside of the bag and having an outer peripheral ring to be clamped between the tank and cover and having means for securing the bag mouth thereto, whereby the bag and frame closes the cross section of the tank adjacent the cover, an encased suction assembly extending partly within the tank and bag and being mounted on said cover, one of said stretchers projecting from the bottom of the encased suction assembly within the bag, and another stretcher projecting outwardly from the tank, whereby a spreading tendency is given the bag as the cover is closed, and means to admit air to the tank on the side of the bag opposed to the suction assembly.

2. A vacuum cleaning apparatus as defined in claim 1, in which the stretcher projecting from the tank extends outwardly around the suction assembly and adjacent to the cover, the stretcher on the bottom of the suction assembly extends only part way into the removable frame, whereby a large area of bag surface, removed from other bag surfaces and free from contact with stretchers, is presented to incoming air.

3. A vacuum cleaning apparatus as defined in claim 1 including a baffle plate assembly closing cross sections of the tank between the air admission means and filtering bag and on which the stretcher projecting from the tank is mounted.

4. A vacuum cleaning apparatus comprising an upright cylindrical tank and a cover therefor, a filtering bag extending into the tank, a plurality of bag stretchers of different diameters supporting said bag in approximately concentric convolutions in said tank, a suction assembly on said cover, said cover and bag being readily removable from said tank, means admitting air tangentially to said tank adjacent the bottom thereof, said means imparting a whirling motion to the incoming air, a baffle plate assembly removably supported in said tank above said means and closing cross sections of said tank, said assembly comprising substantially horizontally extending apertured plates having baffles adjacent some apertures adapted to throw particles from the air prior to its passage through the apertures, one of said bag stretchers being mounted on said baffle assembly, and forming therewith a unit readily removable for cleaning upon removal of the cover, suction assembly and bag.

5. A vacuum cleaning apparatus comprising an upright cylindrical tank and a cover there-

for, a filtering bag extending into the tank, a plurality of bag stretchers of different diameters supporting said bag in approximately concentric convolutions in said tank, a suction assembly on said cover, said cover and bag being readily removable from said tank, means admitting air tangentially to said tank adjacent the bottom thereof, said means imparting a whirling motion to the incoming air, a baffle plate assembly removably supported in said tank above said means and closing cross sections of said tank, one of said bag stretchers being mounted on said baffle assembly, and forming therewith a unit readily removable for cleaning upon removal of the cover, suction assembly and bag.

6. A vacuum cleaning apparatus comprising an upright tank and a one piece cover, filtering media in said tank, a dust laden air entrance in said tank beneath said filtering media, an air exhaust chamber in said cover having an outlet therefrom, the top of said cover having a fluted groove therearound, a motor housing above the cover and fitting closely on said groove, a motor in said housing with a motor shaft extending therefrom, shaft bearings in the top of said cover supporting said shaft the cover top closing the air exhaust chamber from the motor housing, a fan on said shaft in said motor housing drawing warm air from said motor and discharging it through the flutes in said groove, a fan on said shaft in said air exhaust chamber creating a suction in the tank and discharging the air through the outlet of the air exhaust chamber.

7. A vacuum cleaning apparatus comprising an upright filter containing tank and a one piece cover therefor, said cover having upper and lower walls forming therebetween an air exhaust chamber, an outlet from said chamber, a motor above said cover having a shaft passing

through the upper wall of the cover, and a bearing in said upper cover wall for said shaft, a fan on said shaft in said chamber discharging air into the chamber, the cover, motor and fan being readily removable as a unit from the tank for cleaning.

8. A vacuum cleaning apparatus comprising an upright filter containing tank and a one piece cover therefor, said cover having upper and lower walls forming therebetween an air exhaust chamber, an outlet from said chamber, a motor above said cover having a shaft passing through the upper wall of the cover, and a bearing in said upper cover wall for said shaft, a fan chamber formed centrally in the lower wall of said air exhaust chamber, and a fan therein on said shaft, discharging air into the air exhaust chamber, the cover, motor and fan being readily removable as a unit from the tank for cleaning.

9. A vacuum cleaning apparatus comprising an upright filter containing tank and a one piece cover therefor, said cover having upper and lower walls forming therebetween an air exhaust chamber, an outlet from said chamber, a motor above said cover having a shaft passing through the upper wall of the cover and a bearing in said upper cover wall for said shaft, a fan chamber formed centrally in the lower wall of said air exhaust chamber, and a dish shaped cover under the fan chamber having a central opening in the bottom thereof and a fan in said fan chamber, on said shaft, drawing air through said central opening and discharging it into the air exhaust chamber, the cover, motor and fan being readily removable as a unit from the tank for cleaning.

JAMES N. BAKER.
